A. J. MATTER

ELECTRICAL FUSE

Filed Jan. 14, 1921

WITNESSES:

H. J. Wright.

J. E. Scarb

INVENTOR:

Albert J. Matter

UNITED STATES PATENT OFFICE.

ALBERT J. MATTER, OF CHICAGO, ILLINOIS.

ELECTRICAL FUSE.

Application filed January 14, 1921. Serial No. 437,149.

To all whom it may concern:

Be it known that ALBERT J. MATTER, a citizen of the United States, residing at 919 Cornelia Ave., Chicago, Ill., has invented new and useful Improvements in Electrical Fuses, of which the following is a specification.

This invention relates to improvements in electrical fuses and more particularly to that type known as renewable fuses of the screw plug type.

The objects of my invention are; to provide a fuse of this type which may be manufactured with a minimum of insulating material; a minimum number of parts; inexpensive methods of assembling the various parts; insulating parts easy to mould and without threads or inserts to hamper high speed economical production; to provide an inexpensive, easily replaced fusible member; and efficient control of the explosive gases emitted when the fuse "blows".

I attain these objects by means of the improvements herein described and illustrated in the accompanying drawings in which,

Figure 1 is a sectional elevation of the fuse.

Figure 2 is an elevation partially in section showing a modified form of fuse holding terminal plug.

Figure 3 is a bottom view of the cap member shown in Figure 1 and shows the case retaining groove and transparent observation center.

Figure 4 illustrates the fusible member shown in figure 1 in extended form.

Figure 5 shows a modified form of fuse retaining terminal plug.

Figure 6 illustrates still another method of modifying the form of the fuse retaining terminal plug.

Like numerals of reference indicate similar parts throughout the several views.

Referring to the drawings, 1—indicates a ring shaped cap member, preferably made of mouldable insulating material and provided with a central orifice 2, a case retaining groove 3 and indenting recesses 4.

5 is a metallic case, cup shaped and provided with screw threads, 6 or other fuse receptacle engaging and holding means and having an orifice 7 through the bottom, said bottom portion surrounding said orifice be-

ing preferably formed with an inwardly extending flange as shown. 55

To attach the case 5 to the cap 1 it is inserted in groove 3 and locked therein by means of indentations 8 formed in the case 5, with a pointed indenting punch inserted temporarily for this purpose in recesses 4 60 and forming the indentation by force. This permanently locks the edge of the case within the groove of the cap.

Orifice 2 is so formed as to present a shoulder at 9. A transparent observation disc 10, preferably made of mica or other transparent insulating material is forced into the orifice 2 and against the shoulder 9. 65

Referring to Figures 1 and 4, 12 indicates a fuse holding terminal plug perforated at 13 and having a flange 14. This plug is preferably made of moulded insulating material. 15 is a flat strip of fusible material such as zinc and adapted to convey a predetermined amount of electric current. 70 Fuse member 15 has its two ends inserted through orifices 13 and bent back against the flange 14 of fuse holding terminal plug 12 in such manner as to come in contact with the metallic case 5 when the plug is inserted in orifice 7 of case 5. The plug is made to fit snugly in the orifice so that slight pressure will force it securely into place. 75

Fuse member 15 is preferably provided with perforations 16 so as to diminish the cross sectional area at these points of the fuse member thus causing it to fuse at the sides of the perforations when the electrical current exceeds that for which the fuse is designed, thereby severing the fuse member at these points and permitting intermediate parts to drop away so as to completely break the electrical circuit. 80

The complete fuse as described comprises a threaded case of electrical current conducting material, a cap therefor composed of non-conducting material a fuse holding terminal plug composed of non-conducting material and a fuse member of fusible electrical current conducting material whose ends come in contact with the case and whose intermediate portion 15^a forms a terminal contact point. 85

In use the fuse is screwed into the usual threaded fuse receptacle so that the terminal 105

contact point 15^a is forced into electrical contact with the inner electrical terminal of the fuse receptacle, thereby closing the circuit by permitting the electrical current 5 to pass through the fuse receptacle, fuse case 5, fuse member 15 and the inner terminal of the fuse receptacle.

In the event of excess current and consequent blowing of the fuse this may be 10 observed through the transparent disc 10 without removing the fuse from its receptacle.

In Figure 2 the fuse plug 12^a is provided with a single perforation 17, a recess 18, and 15 a flange 14^a. The fuse member 19 in this instance is of cylindrical form with a terminal head 20.

The modification shown in Figure 5 illustrates a fuse plug 12^c perforated at 21, 20 flanged at 14^c and recessed at 22. 23 is a metallic terminal post provided with a fuse attaching screw 24 and having a terminal contact head 25. 26 is a fuse member perforated to receive screw 24 and arranged to 25 fit into recesses 22. A metallic fuse holding ring 27 is adapted to snugly enclose the fuse ends and is arranged to come in contact with the case 5.

In Figure 6 the fuse plug 12^d is shown 30 perforated at 28 and flanged at 14^d. 29 is a metallic terminal post which is slotted at 30 to receive one end of a fuse member 31 and is provided with a terminal contact head 32. The plug 12^d is provided with a 35 recess at 33 adapted to receive one end of the fuse member 31 and hold it in contact with case 5.

It is understood that the method of holding the fusible member may be still 40 further modified in a fuse of this type comprising a case, cap and plug.

What is claimed is:

1. The combination of a metallic case 45 having an inturned edge, a non-conducting cap permanently attached thereto, a fuse and a non-conducting plug carried by said metallic case adapted to hold the fuse between it and the inturned edge of the case.

2. The combination of a metallic case 50 having an inturned edge, a non-conducting non-threaded cap attached thereto, a fuse and a non-conducting plug adapted to hold the fuse between it and the inturned edge of the case.

3. The combination of a threaded metallic case having an inturned edge, a non-conducting non-threaded cap attached thereto, a fuse and a non-conducting plug adapted 55 to hold the fuse between it and the inturned edge of the case.

4. In a renewable fuse the combination of a threaded case having an inturned edge, a non-threaded cap attached thereto and a removable plug adapted to hold a fuse 60 between it and the inturned edge of the case.

5. In a renewable fuse the combination with a fuse case of a cap having a groove adapted to receive the edge of said case and provided with orifices through the side thereof for the purpose of indenting the 70 case to hold it within said groove.

6. In a renewable fuse the combination with a fuse case having an open end of a cap having an annular groove adapted to receive the edge of the open end of said case and means for fastening said case edge within said groove after the cap is made. 75

7. In a renewable fuse the combination of a metallic fuse case having an inturned edge, a ring-shaped non-conducting cap 80 permanently attached thereto having a central orifice and having a transparent closure for said orifice and a renewable non-threaded plug adapted to hold a fuse between it and the inturned edge of the case. 85

8. In a renewable fuse the combination with a fuse case of a ring shaped insulating cap having a groove and radially disposed perforations leading through said cap to 90 said groove for the purpose set forth.

9. In a renewable fuse the combination with a fuse case of a cap having a groove adapted to receive the edge of said case and having recesses extending to said groove and indentations applied to the edge of said case within said groove through said recess for the purpose of fastening said case to the aforesaid cap. 95

10. In a renewable fuse the combination with a case of an insulating perforated cap having a transparent center and provided with a groove and radially disposed perforations through said cap to said groove for the purpose set forth. 100

11. In a renewable fuse the combination with a case having an open end of an insulating perforated cap having an annular groove adapted to receive the open end of said case after said cap is completed. 105

12. In a renewable fuse the combination with a case of a perforated cap having an annular groove adapted to receive the edge of the case after the cap is made and provided with radially disposed indentations into which the edge of the case is crimped. 110

13. The combination with a case having an inturned edge of a perforated fuse holding plug adapted to hold a wire-nail-shaped fuse in said perforation and in direct contact with said case one end of said fuse being held between the plug and the inturned edge of said case. 115

14. The combination with a fuse case having an inturned edge and a renewable, perforated, non-threaded plug of a wire-nail-shaped fusible current conducting fuse member having an enlarged terminal head, said fuse member being adapted to pass through said plug with the enlarged head adjacent and outside of said plug and the 120 125 130

- opposite end held between the plug and the inturned edge of said case.
15. In a renewable fuse the combination with a cup-shaped metallic fuse case having a perforated bottom, of a non-conducting cap having annular recesses therein and adapted to receive the open end of said case so that the edge thereof may be indented into said recesses for the purpose of securing said cap to said case.
16. In a renewable fuse having a removable insulating fusible member holding plug, a metallic cup-shaped case having a perforated bottom with an axially disposed inturned annular flange adjacent to the edge of said perforation, adapted to receive said plug.
17. In a renewable plug having a removable insulating fusible-element holding plug, a metallic cup-shaped case having a perforated bottom with an axially disposed annular flange adjacent to the edge of said perforation, adapted to receive said plug.

In testimony whereof, I have signed my name to this specification this 11th day of January 1921.

ALBERT J. MATTER.
